UNITED STATES PATENT OFFICE

JOSEPH FRED BANGERT, OF WILLIAMSPORT, PENNSYLVANIA

LINTYPE-MAGAZINE RACK

Application filed June 12, 1930. Serial No. 460,670.

This invention relates to an improved structure which may be generally entitled a magazine rack, and it has more particular reference to a unitary support for storage of extra magazines such as are used in association with linotype and intertype machines.

The improved structure has been designed with a view toward protecting and reserving the usual lower cross-bar on the magazine. 10 This bar, when placed on the machine, previous to seating the same in the escapement box, is the guiding point of said seating in the box, and under present conditions of storage on slides of steel or other metal, the continuous sliding in or out of the magazine on this lower cross bar, with its full capacity weight of around seventy-four pounds, eventually causes wear on said cross bar.

This therefore prevents desirable and perfect seating in the escapement box. When perfect seating does not take place, there is a tendency for said escapement box to injure the lower escapement box entry on the magazine, thereby preventing free running of the mats in the magazine and eventually decidedly injuring the magazine and frequently rendering it useless.

The purpose of the present invention is to provide a simple and economical form of support and rack structure which will enable the magazine to be racked or stacked in close proximity in an out-of-the-way convenient position while dormant and not in use, and in carrying the inventive conception into practice, I have developed a particular form of structure which, it is believed, will accomplish this result in a practical and dependable manner without injury to the magazine.

The particular structural details and their relative association and arrangement will become more readily apparent from the following description and drawings.

In the drawings:

Figure 1 is a perspective view of a complete rack constructed in accordance with the present invention.

Figure 2 is a perspective view of one of the roller equipped channel irons of the type used in connection with the linotype machine.

Figure 3 is a view like Figure 2 showing

the rollers disposed for use and association with an intertype machine.

Figure 4 is an end view of the structure seen in Figure 3.

Figure 5 is an end view of the structure seen in Figure 2.

Figure 6 is an enlarged fragmentary detail section taken approximately on the plane of the line 6—6 of Figure 2.

Figure 7 is a section taken approximately on the plane of the line 7—7 of Figure 1.

Referring to Figure 1 of the drawings, it will be seen that the numeral 8 designates a stand embodying a plurality of corner legs 9, a bracing frame 10, and frame 11 at the top, constituting what may be designated as a table. Supported above the table through the medium of legs 12 is a confining and guiding openwork cage 13 for the magazine (not shown).

The numeral 14 merely designates a frontal or crown piece which is in the nature of an angle iron, and the numeral 15 represents the end iron and 16 the back iron whose flange constitutes a stop for preventing rearwardly displacement of the magazine.

Depending from and detachably connected to the frontal bar 14 in longitudinally spaced points are guides 17. Arranged on the table beneath the guides, are the roller equipped channel irons 18. These are disposed in side-by-side spaced parallelism and in a horizontal plane. As seen in Figure 6, the web portion 19 of each iron is apertured to accommodate the screw-threaded stem 20 of a bolt. The numeral 21 designates a retaining nut on the stem.

The bolt includes a smooth central portion 22 having a retaining head 23. Mounted on this spindle and held in place by the head is a flanged roller 24. These rollers are arranged in a horizontal plane and in alinement with each other as seen in Figures 2 and 3. The rollers provide anti-friction sliding support means for the magazines as they are put in position and removed from the cage.

The rollers and irons 18 are located in proper alinement with the guides 17 at the top. As before stated, in the form of the invention seen in Figure 2, the rollers are lo-

cated for accommodating magazines of the linotype species. In Figure 3 however, the rollers are located near the bottom for better accommodating magazines of the type used in connection with intertype machines.

5 In operation, it is understood that the individual magazines are stacked in vertical or perpendicular relationship in the cage 13 and held in place by the legs 12 and the retaining bars 15 and 16 as well as the guide means 17 and the roller equipped channel irons 18. This provides for effective and expeditious storage of extra magazines while the latter are not in use on the machines.

10 15 The gist of the invention comprehends the provision of an appropriate support characterized by a leg-equipped table provided with a multiplicity of longitudinally spaced parallel roller equipped channel irons constituting the seating means for the extra magazines. In addition, it takes into consideration the elevated cage-like frame 13 characterized by the legs 12 and the top structure having the guide means 17 so located as to 20 25 co-operate with the rollers on the irons 18.

It is thought that persons skilled in the art to which the invention relates will be able to obtain a clear understanding of the invention after considering the description 30 in connection with the drawings. Therefore, a more lengthy description is regarded as unnecessary. Minor changes in shape, size, and rearrangement of details coming within the field of invention claimed may be resorted to 35 in actual practice if desired.

I claim:

1. In a structure of the class described, a leg supported table, a plurality of longitudinally spaced transversely disposed spaced 40 parallel channel irons on said table, a plurality of magazine supporting rollers mounted for rotation on each of said channel irons and retaining means extending above said table for confining the magazines in racked 45 relationship on said rollers, comprising an open-work cage including vertical legs and a top structure thereon including a rear stop and a frontal piece, said frontal piece being provided with depending longitudinally 50 spaced guides disposed in substantial vertical alignment with said channel irons.

2. In a magazine rack of the class described, a table, supporting legs therefor, a cage-like frame supported above said table and including corner legs and a stop structure supported from said legs and including a rear stop member and a frontal piece having a plurality of longitudinally spaced depending guides, and means on the table beneath said guides for individually supporting a plurality of racked magazines.

3. In a magazine rack of the class described, a table, supporting legs therefor, a cage-like frame supported above said table

and including corner legs and a stop structure supported from said legs and including a rear stop member and a frontal piece having a plurality of longitudinally spaced depending drives, and means on the table beneath 70 said drives for individually supporting a plurality of racked magazines, comprising a group of transversely disposed longitudinally spaced parallel irons provided with a plurality of anti-friction seating rollers. 75

In testimony whereof I affix my signature.

JOSEPH FRED BANGERT.
